US00D855300S

(12) **United States Design Patent** (10) Patent No.: **US D855,300 S**
(45) Date of Patent: ** Aug. 6, 2019

(54) **SHOE**

- (71) Applicant: **Reebok International Limited**, London (GB)
- (72) Inventors: **Robert Bischoff**, Attleboro, MA (US); **Matthew Boudreau**, North Attleboro, MA (US)
- (73) Assignee: **Reebok International Limited**, London (GB)
- (**) Term: **15 Years**
- (21) Appl. No.: **29/623,169**
- (22) Filed: **Oct. 23, 2017**

Primary Examiner — T Chase Nelson*(74) Attorney, Agent, or Firm* — Sterne, Kessler, Goldstein & Fox P.L.L.C.**CLAIM**

The ornamental design for a shoe, as shown and described.

DESCRIPTION

FIG. 1 is a bottom perspective view of a shoe showing the claimed design;

FIG. 2 is a top plan view thereof;

FIG. 3 is a bottom plan view thereof;

FIG. 4 is a side view thereof;

FIG. 5 is another side view thereof;

FIG. 6 is a front view thereof; and,

FIG. 7 is a rear view thereof.

The broken lines in the figures show portions of the shoe that form no part of the claimed design.
